UNITED STATES PATENT OFFICE.

FREDERICK H. PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,002,864.

Specification of Letters Patent.

Patented Sept. 12, 1911.

Application filed August 26, 1905. Serial No. 275,959.

To all whom it may concern:

Be it known that I, FREDERICK H. PERRY, a citizen of the United States, residing at Beverly, in the county of Essex and Commonwealth of Massachusetts, have invented certain Improvements in Machines for Inserting Fastenings, of which the following description, in connection with the accompanying drawings, is a specification, like reference characters on the drawings indicating like parts in the several figures.

This invention relates to machines for inserting fastenings for securing together layers of material, or for inserting slugs or other devices which are intended for purposes of ornamentation or resisting wear, the word "fastenings" being hereinafter used, for brevity and convenience, to designate and include any and all materials and devices which may be used for the purposes named. Machines of this type are used extensively in the manufacture of shoes for attaching the outersole of a shoe to its innersole or for ornamenting the tread face of the heel or sole. It has been the practice heretofore to use such machines to insert one continuous row of fastenings in the tread face of the heel of a shoe in a line conforming to the outline of the heel, and a second row of fastenings inside of the first extending for a portion of the length of the first row. The means for controlling the insertion of the fastenings of the inside row, however, was manually operated, and because of this the inside row of one shoe of a pair would often contain more or less fastenings than the corresponding row in the other shoe of the pair, and would also often occupy a different position in the surface of the heel, on account of the inability of the operator to commence and discontinue the insertion of the fastenings of the inside row at just the proper point in the cycle of operations of the machine. This lack of uniformity in the inside rows detracted greatly from the appearance of the pair of shoes when finished.

One important feature of the invention consists in automatic means for inserting fastenings in a predetermined design, preferably in combination with means for varying the operation of the machine to change the design in which the fastenings are inserted.

Another feature of the invention is the

combination of means for inserting a plurality of different kinds or rows of fastenings with means for controlling automatically the insertion of fastenings of one kind, or the fastenings in one row, without affecting the insertion of fastenings of a different kind or the fastenings in a different row.

A further feature of the invention consists in automatic means in a machine of the class mentioned for discontinuing the insertion of fastenings of one kind or in a certain row while the machine continues in operation, either to feed the stock, as usual, or, in addition, to insert fastenings of other kinds or in different rows. Preferably there is employed, also, means for inserting a certain number of fastenings, then discontinuing the insertion of fastenings for a certain number of operations of the machine and thereafter resuming the insertion of fastenings.

A further feature of the invention consists in means for varying the time of operation of the means, mentioned above, which causes the insertion of the fastenings to be discontinued automatically for a certain number of operations and thereafter to be resumed.

Other features of the invention will be hereinafter pointed out.

The preferred form of the invention is herein shown as embodied in a machine for forming fastenings from continuous material, such, for example, as wire, and inserting them into stock, said machine being adapted to operate upon a plurality of strands of wire, so that a plurality of fastenings may be inserted simultaneously. Said machine comprises automatic means for causing the feeding of one strand of wire to be discontinued for a certain number of operations of the machine and thereafter resumed without affecting the operation of feeding the other strand or strands of wire. The machine also comprises means under control of the operator for varying the time of operation of said automatic means so that the sequence in which the fastenings are inserted may be varied. Manually-operated means is also provided for rendering said automatic means inoperative while other elements of the machine continue in operation.

The machine has mechanism for feeding a plurality of strands of wire into position to

be severed to form fastenings which thereafter are carried into alinement with drivers that force them into the stock. In the machine herein shown the stock is fed intermittently by an awl and preferably in a path determined by the contour of the work, but it should be understood that the invention is not limited to this particular kind of feeding mechanism, as the stock 10 may be fed by any desired means, such, for example, as a feeding mechanism which acts on the edge of the stock.

A movable dial or pattern device, having adjustable controlling pins, is provided for 15 governing the operation of the wire-feeding mechanism for one strand of wire, and the position and arrangement of said controlling pins may be changed to cause the feeding mechanism to feed said strand at each 20 operation of the machine or intermittently during the operations of the machine, thereby enabling the fastenings formed from this strand to be inserted in any sequence to produce a predetermined design. Means is provided for restoring the dial to starting position whenever the machine is stopped, so 25 that the same design may be produced repeatedly on different pieces of stock, and for enabling the same design to be produced on 30 the heel of either a right or a left shoe, additional means is provided for adjusting the dial. Independent means is also provided for causing the dial to remain inoperative while the other elements of the machine continue in operation, and when in its inoperative position a controlling pin on said dial can be so adjusted as to cause the feeding mechanism either to act on the wire at each 35 operation of the machine or not at all.

40 In the drawings, Figure 1 is a front elevation of a machine embodying the preferred form of my invention; Fig. 2 is an elevation of the right-hand side of the machine shown in Fig. 1; Fig. 3 is a detail view looking 45 toward the rear of the machine taken on the line 3-3 of Fig. 2; Fig. 4 is a perspective front view of the dial or pattern device which controls the feeding of one strand of wire and the operating mechanism for said 50 dial; Fig. 5 is a detail plan view partly in section, taken on the line 5-5 of Fig. 9, showing the wire-feeding mechanism; Fig. 6 is a detail view of one of the pawls which actuates the wire-feeding rolls; Fig. 7 is a 55 sectional view of a portion of the dial or pattern device showing the plunger for moving the controlling pins on the dial into operative position; Fig. 8 is a perspective view of a pair of controlling pins and the 60 spring used for holding them in position; Fig. 9 is a detail view taken on the line 9-9 of Fig. 2 looking toward the front of the machine; Fig. 10 is a perspective rear view, partly in section, of the dial; Fig. 11 65 shows some of the designs in which fasten-

ings may be inserted by this machine; and Figs. 12 and 13 show, respectively, the tread faces of the heels of a right and a left shoe.

The invention is herein shown as embodied in a machine of the type shown in 70 United States Patent No. 786,190 to L. A. Casgrain, March 28, 1905, to which reference may be had for the description of parts not herein fully described.

Referring to the drawings, A designates 75 a base or standard which supports the head A' that carries the main shaft C. The coils of wire W and W' from which the fastenings are formed are carried by reels r⁶ and r^{6'} supported by brackets r and r' fastened 80 to the head of the machine, the strands of wire w and w' being drawn from the centers of said coils and fed into position to be severed to form fastenings, by feed rolls a⁶ and a^{6'} which are mounted on a stud shaft 85 y in the head of the machine, as shown in Figs. 5 and 9. Coöperating with said feed rolls are presser rolls a⁷ and a^{7'} that are mounted in a yoke a⁸ adjustably fastened to the head of the machine by a screw a⁹. 90

As shown in Fig. 5, the feed roll a^{6'} is connected to the sleeve or hub of a ratchet wheel a^{5'} mounted on the stud shaft y, and adjacent to said roll is the feed roll a⁶ connected to a ratchet wheel a⁵ which rotates 95 on ball bearings on the sleeve or hub of ratchet wheel a^{5'}. A pawl-carrying sleeve a² provided with an arm a³ carrying a plurality of pawls a^{4'} and a⁴ which coöperate, respectively, with the ratchet wheels connected to the feed rolls a^{6'} and a⁶, is oscillatingly mounted on the stud shaft y, and said pawl carrier is also provided with a second arm having a roller a¹⁰ that is acted 100 upon by a cam a¹² on the cam block a¹³ carried by the main shaft. Two pawls are provided for each ratchet wheel, and for insuring that the pawls will remain normally in engagement with the ratchet wheels, each pawl is oscillatingly mounted on the stud 105 2 fastened to the pawl carrier and is forced toward the ratchet wheels by a spring 3 fastened at one end to the stud and at the other end to the pawl, as shown in Fig. 6. A coiled spring S², which at one end is connected to the head of the machine and at 110 its other end to the pin 2 on the pawl carrier, restores said pawl carrier to its normal position after it has been actuated by the cam a¹². Mounted in the head of the machine, as shown in dotted lines in Fig. 2, is a sleeve k⁸ in which a shaft k⁹ is reciprocatingly mounted, said shaft carrying at its forward end a throat k⁷ provided with openings to receive the strands of wire. After 115 the wire has been fed into said throat the sleeve k⁸ is oscillated by means of the lever k¹³ fastened thereto and actuated from a cam-groove in cam block a¹³ to cause the cutting blade m carried by said sleeve to co- 120 125 130

operate with the stationary cutter m^4 for severing the strands of wire to form fastenings, the shaft h^3 being thereafter reciprocated longitudinally of said sleeve by means 5 of lever h' , pivoted at 90 to the head of the machine and actuated by cam h , on the main shaft, to place the fastenings in the throat h^7 in alinement with the drivers b^5 , b^5' on driver bar b^4 which force the fastenings into 10 the stock clamped between the foot plate n and the horn B .

An awl bar 91 provided with an awl h is reciprocatingly mounted in an oscillating frame i and is adapted to feed the stock and 15 also form holes therein to receive the fastenings formed from the strand of wire w , said awl bar being actuated by an arm h' fastened to a rockshaft h^2 provided with a second arm h^3 having a roll that travels in a cam groove 20 in the cam block h^5 on the outer end of the main shaft, as shown in Fig. 1. After the awl bar has been moved downwardly to force the awl into the stock, the frame i is oscillated to move the awl bar laterally for 25 feeding the stock, and the awl bar is then moved upwardly and the frame oscillated in the opposite direction to restore the awl bar to normal position, the means for oscillating the frame i comprising an arm i^7 actuated 30 by a cam groove in the cam block a^{13} and being fastened to a rockshaft provided with an arm i^{5x} that is connected to the frame i .

The main shaft carries at its rear end a cam disk C' , the periphery of which forms 35 one member of a friction clutch, the coöperating member C^2 of said clutch being continuously driven by a belt (not shown) and being adapted to be moved into and out of engagement with the cam disk C' by means 40 of a wedge-shaped block C^6 attached to a rod C^7 under control of the operator, said rod being held normally depressed by a spring C^8 to cause the clutch to remain inoperative. The disk C' has on its inner face a cam c , 45 see Fig. 3, against which is held a roll c^1 on a lever c^2 pivoted on a stud c^4 secured to the head of the machine, the lower end of said lever being connected by an adjustable link 93 to one member 94 of a brake shoe 50 which embraces the rim of the disk C' , the other member 95 of said brake shoe being fastened to a stationary part of the machine. At the lower end of lever c^2 is a notch which receives a stud 97 projecting from the rod C^7 , 55 so that the spring C^8 which holds said rod normally depressed also operates to hold the roll on lever c^2 in engagement with the cam c . The cam c is provided with a groove which receives a roll c' on a lever c^2 pivoted 60 on a stationary stud c^3 and having connected to its outer end a link c^4 that forms part of the mechanism for depressing the horn intermittently for unclamping the stock to permit it to be fed, as is common in machines 65 of this type.

The inner or right-hand end of lever e^2 is notched at e^5 to be at times engaged by a pawl f pivotally connected to a pawl carrier f^2 oscillatingly mounted on the stud e^3 , said pawl carrier having a roll f^4 to be acted upon by a species of tappet cam f^5 . A housing f^6 on the pawl carrier receives a spring s' which, resting at its lower end on a fixed part of the head, maintains the roll f^4 in engagement with the tappet cam f^5 . The 70 pawl f is governed as to its engagement with the lever e^2 by a pawl controller f^7 pivoted to the lever e^2 and having a beveled lug f^8 and a notch on its upper side near its extremity to coöperate with a tooth on the side 80 of the pawl f , a spring s^2 pressing the pawl controller toward said tooth, as shown in Fig. 3. When the rod C^7 is raised to start the machine, the lever e^2 is swung thereby to the right, viewing Fig. 3, so that the tooth 85 on the pawl f will enter the notch of the pawl controller f^7 , the spring s^2 yielding slightly to allow it to pass over lug f^8 and the continued movement of lever e^2 drawing the pawl f from the 90 notch e^5 of the lever e^2 . So long as the rod C^7 is held elevated to cause the members of the clutch to remain in engagement, it will be impossible for pawl f to engage lever e^2 as the pawl carrier is oscillated back and 95 forth by the tappet cam during the rotation of the main shaft, but when said rod is allowed to descend, the lever e^2 will move to the left of Fig. 3 and the pawl controller f^7 will move the pawl f so that it will engage the 100 notch e^5 in the right-hand end of the lever e^2 . The tappet cam f^5 is so positioned on the main shaft that it will actuate the pawl carrier f^2 immediately after the pawl f has engaged the notch in lever e^2 and will depress 105 said pawl carrier and rock lever e^2 for lifting the rod e^4 and finally depressing the horn far enough to permit the stock to be removed therefrom. The brake is applied at the time the highest part of the tappet cam 110 f^5 engages the roll on the pawl carrier f^2 , so that the machine is stopped with the horn depressed, the parts being in the position shown in Fig. 3.

The parts so far specifically described and 115 referred to are substantially the same as those shown and described in the patent referred to, except that the machine herein shown is adapted to drive fastenings formed from two strands of wire, and accordingly 120 has been provided with an additional driver b^5' and feed roll a^6' , and the throat h^7 is provided with an additional opening to receive the strand of wire w' .

In order that fastenings may be inserted 125 in predetermined designs, such, for example, as shown in Fig. 11, means is provided for controlling automatically the insertion of the fastenings formed from the strand of wire w' , said means comprising a dial or 130

pattern device 10 which actuates mechanism that causes the feed roll a'' to become operative or inoperative while the machine continues in operation, whereby the strand of wire w' will either be fed forward to form a fastening or will not be acted upon. The dial 10 is rotatably mounted on a stud 12 screwed into a bracket 14 (Fig. 9) fastened to the head of the machine, and is provided on its periphery with ratchet teeth 11 that are engaged by a pawl 16 pivoted to the arm h' that actuates the awl bar, see Figs. 1 and 9, whereby said dial is moved one step forward in the direction of the arrow a in Fig. 1 at each cycle of operations of the machine, the dial being prevented from retrograde movement by means of a locking dog 18 pivoted at 19 to a portion of the bracket 14. When the machine is stopped the dial is returned to starting position by a coiled spring 20 which is fastened at one end to the head of the stud 12 and at its other end to a pin or stud 21 on the dial, as shown in Fig. 10. Adjustably mounted in the dial are a plurality of controlling pins 22 adapted to be moved into operative position, as shown in Fig. 7, or as indicated by the groups of pins x , y and z , in Fig. 4, and when in such position said pins engage and elevate the end 24 of lever 26 pivoted on the stationary stud 28 carried by the bracket 14 and having fastened to its lower end a link 29 that is connected to the controlling lever 30. The hub of the controlling lever 30 is mounted on a bearing 31 supported by the extended end of the stud 12, as shown in Fig. 10, and said lever is provided at its lower end with a shoe 32 which engages rollers 39 carried by the pawls a'' and holds them out of contact with the ratchet wheel a' of feed roll a'' whenever said controlling lever is moved inwardly as the end 24 of lever 26 is elevated. The controlling pins 22 are moved outwardly into operative position by means of a plunger 33 mounted in a sleeve 34 fastened to the bracket 14 and surrounded by a coiled spring 37, as shown in Fig. 7, the operator moving the dial to bring the desired pin into alignment with said plunger. For restoring the pins to inoperative position a device 35 formed of spring metal is rotatably mounted on the stud 12 and is provided with an inwardly-projecting finger 36 that engages a controlling pin and moves it inwardly as the operator presses said device in the direction of the arrow in Fig. 7, said device being adapted to be moved to any point on the dial, as shown by dotted lines in Fig. 4, to bring the finger 36 into position to engage any pin. It will be seen that with mechanism of this description it is possible to insert fastenings formed from the strand w' in any desired sequence as the controlling pins on the dial govern the operation of the controlling lever 30 which governs the feed-

ing of the strand, and accordingly comprises the means for governing the insertion of the fastenings. Fig. 4 shows the controlling pins on the dial arranged to produce the design Q of Fig. 11, the pins being arranged in alternate groups of three pins in operative position and three pins in inoperative position, so that the end 24 of lever 26 will be held elevated for three consecutive operations to cause the pawls which actuate the feed roll a'' to remain inoperative for that period, then permitted to assume its normal position for three consecutive operations, so that said pawls can actuate the roll a'' to feed the strand of wire w' for that period, etc. When alternate pins on the dial are moved into operative position, the design R of Fig. 11 will be produced, and if all the controlling pins are moved into operative position the roll a'' will not act on strand w' , and no fastenings will be formed thereby.

For preventing too free movement of the controlling pins and insuring that they will remain in either operative or inoperative position, U-shaped springs 80 are mounted in the dial and engage notches formed in the pins, as shown in Fig. 8.

In order that the same design may be produced repeatedly on different pieces of stock, the dial is arranged to be returned by the spring 20 to starting position whenever the machine stops, this being effected by the following mechanism. A rockshaft 40 which is mounted in the head of the machine has at its rear end an arm 41 that is connected by a link 42 to a pin 43 on the horn-depressing lever e^2 , said link having a slot 44 which receives the pin 43 so that the normal movements of the lever e^2 for depressing the horn to permit the stock to be fed will not impart movement to link 42. When the machine stops, however, the extra movement which is imparted to lever e^2 , as previously described, will cause the link to be actuated and thereby rock the shaft 40. At the front end of said shaft is an arm 46 connected by a link 47 to a pin 48 on the locking dog 18, said shaft being provided with a second arm 49 which contacts with the pawl 16, as shown in Fig. 4. The locking dog 18 is provided with a pin 501 which passes under the lever 26, so that when the shaft 40 is rocked as the machine comes to rest the link 47 will elevate the locking dog and also move the end 24 of lever 26 out of position, to be engaged by the controlling pins on the dial, and the arm 49 will move the pawl 16 out of engagement with the ratchet teeth on the dial, thereby releasing the dial and permitting the spring 20 to return it to starting position. When the machine is again started the rockshaft is rocked back to normal position by means of a spring 69 (Fig. 3) fastened at one end to the arm 41 and at its

other end to a stationary bracket 66, and the pawl 16 and locking dog 18 are again moved into engagement with the teeth on the dial by means of a leaf spring 191 carried by the pawl and a coiled spring 81 fastened at one end to the pin 48 and at its other end to the bracket 14. The link 47 which moves the locking dog 18 is provided at its upper end with a head 83 having a slot that receives the pin 48 on the locking dog, as shown in Fig. 9, so that when the rockshaft 40 occupies its normal position and the link 47 is depressed, said locking dog can oscillate slightly on its pivot as its lower end is engaged by the teeth on the dial. The starting position of the dial is governed by a stop lever 50 mounted on the bearing 31 and within the hub of the controlling lever 30 and provided with a stop 51 that co-operates with a stop 52 on the back of the dial. A spring abutment 53 adjustably held in position in the bracket 14 by a clamp nut 55, controls the position of the stop lever which is held normally in contact therewith by a coiled spring 54 fastened at one end to said lever and at its other end to the head of the machine.

From the foregoing description it will be seen that when the machine is at rest the pawl 16 and locking dog 18 are disengaged from the ratchet teeth on the dial so that said dial can be manually rotated to bring any one of the controlling pins on the dial into alignment with the plunger 33 that moves said pins into operative position, the stud 21, which is extended from the front of the dial, being adapted to be grasped by the operator for this purpose. The dial may be temporarily locked in any position to which it has been moved, by means of a manually-operated spring-pressed plunger 60 mounted in a sleeve 61 fastened to the bracket 14 and having a tapered end which engages the teeth on the dial when said plunger is depressed.

A rim 84, which surrounds the dial and which forms part of the bracket 14, is provided with a projection 85 that is in alignment with the plunger 33, thereby enabling the operator to tell just how far he must move the dial to place in alignment with the plunger 33 the controlling pin which it is desired to move into operative position. Said rim has openings through which the pawl 16, dog 18, lever 26, and plunger 60 project, and is also provided with a second projection 86 which is directly above the first effective pin on the dial when said dial is in its starting position.

As the number of fastenings which would be inserted in the sole or heel of a shoe of any size is less than the number of controlling pins on the dial, said dial never makes a complete revolution when shoes are being operated on, before the machine is stopped

to place upon the horn the next shoe in which the fastenings are to be inserted. If, however, a piece of stock larger in dimensions than the periphery of a shoe sole should be operated on, and it should be desired to insert more fastenings than the number of controlling pins on the dial, the continued operation of the machine would cause the dial to make more than one complete revolution, thereby causing the stop 52 on said dial to engage and displace the stop lever 50, probably resulting in damage or breakage of some part of the machine. To prevent this from occurring, the dial is provided in its periphery with a notch 87, and when the dial is in its starting position said notch occupies the position relatively to the pawl 16, shown in Fig. 4. One complete revolution of the dial carries the notch into position to be engaged by the pawl 16, and as there are no teeth in said notched portion, the pawl cannot impart further movement to the dial, the operator then stops the machine, and the spring 20 returns the dial to starting position.

Manually-operated means is also provided for actuating the rockshaft 40 to cause the pawl 16 and locking dog 18 to be disengaged from the dial and permit the dial to remain inoperative while the other elements of the machine continue in operation. This enables the feed roll α' either to feed the strand of wire w' at each operation of the machine or not feed said strand at all, without necessitating the adjustment of all the pins on the dial in either operative or inoperative position, for if the dial remains inoperative and the controlling pin which is in alignment with the end of the lever 26 is moved into operative position the free end of said lever will be held elevated and the feed roll α' will remain inoperative and no fastening from coil W' will be inserted, but if said pin occupies its inoperative position the lever 26 will assume its normal position and the roll α' will feed wire from coil W' at each operation of the machine. The means for manually rocking the shaft 40 and holding it in this position comprises a dog 65 pivoted at 67 to a bracket 66 on the head of the machine and adapted to be moved into the dotted line position shown in Fig. 3 to cause its end 68 to engage the arm 41 fastened to said shaft and rock it.

The end 68 of dog 65 is so formed that when moved downwardly from the full-line position of Fig. 3 it will rock shaft 40 sufficiently to disengage the pawl 16 and locking dog 18 from ratchet teeth 11, but not sufficiently to bring pin 501 into engagement with lever 26, and thus carry its end 24 to a position where it cannot engage pins 22. Preferably dog 65 is so constructed that, if desired, shaft 40 can be rocked still farther than to the position above indicated, so that

pin 501 may engage and move lever 26 and the parts will all occupy the same positions as they do when the horn is released and the machine is at rest. This may be done, as shown, by providing the end 68 of dog 65 with two steps each of which, when brought into contact with arm 41, will give a different angular movement to shaft 40.

One design which it has been the practice heretofore to produce, but which has never been produced satisfactorily for the reasons previously referred to, is shown in Figs. 12 and 13, in which one continuous row of fastenings is inserted in the tread face of a shoe heel in a line conforming to the outline of the heel, and a second row of fastenings is inserted inside of the first row for a portion of the distance of said row. To produce this design, by means of this machine, on the heel of a right shoe requiring forty-four slugs to form a complete line around its periphery, the first twenty-two controlling pins on the dial are moved into operative position, the next twelve are left inoperative, and the next ten pins on the dial are moved into operative position, so that when the machine is started the free end of the lever 26 will be held elevated during twenty-two operations of the machine to cause the feed roll a'' to remain inoperative, said lever then assuming its normal position for the next twelve operations of the machine to permit the roll a'' to feed the wire w' at each cycle of operations to form fastenings, and then being again elevated while the remaining ten fastenings of the outside row are being inserted. When inserting fastenings in the heel of a right shoe, the first fastening is inserted at the inside corner ic of the breast of the heel, the shoe being fed and turned in the direction of the arrow in Fig. 12 to cause the fastenings to be inserted in a line conforming to the contour of the heel, the last fastening being inserted at the outside corner oc of the breast. As both right and left shoes are placed on the horn in the same position, namely, with the toe portion of the shoe extending to the left of the operator as he faces the machine, as shown in Fig. 1, it is apparent that the first fastening which is inserted in the heel of a left shoe will be inserted at the outside corner oc of the breast of the heel and the last fastening at the inside corner ic of the breast. Consequently, when the heels of a pair of shoes are provided with inside rows of fastenings extending for only a portion of the distance of the outside rows it is necessary that the first fastening of the inside row be inserted at a different point in the cycle of operations of the machine when the left shoe is being operated on, in order that the inside row of each shoe will occupy a corresponding position in the tread face of the heel. To obtain this result without having

to change the position of the controlling pins on the dial when right and left shoes are being operated on, means are provided for changing the starting position of the dial when fastenings are being inserted in the heel of a left shoe, said means comprising a hand-operated lever 70 pivoted on the shaft h^2 and connected by means of a link 72 with the stop lever 50, so that by moving the free end of the hand-operated lever 70 inwardly the stop lever will be moved in the direction of the arrow in Fig. 9 and cause the stop 51 carried thereby to engage the stop 52 on the dial and rotate it forwardly a distance equal to that which it would be moved by the pawl 16 during twelve operations of the machine. The lever 70 is connected to the link 72 by a pin 911 on the lever engaging a cam slot 901 in the end of the link, and said link is also provided with a lug 931 which rides up the inclined end of the head 83 of link 47 whenever the free end of said lever is moved inwardly, the action of the pin 911 in the slot 901 drawing the link 72 downwardly, so that the lug will catch behind the head 83, as shown in dotted lines in Fig. 9, and thereby hold the stop lever 50 and the dial in their adjusted position.

When the machine is started the link 47 will be depressed, as previously described, and as the head on said link moves out of engagement with the lug on link 72 the spring 54 will operate to return the stop lever to normal position, but the dial will be prevented from rotating rearwardly by means of the locking dog 18 which engages the teeth on the dial before the depression of link 47 releases the link 72. When the dial is in this position and the machine is started, the end 24 of lever 26 will be held elevated for only ten operations of the machine, then allowed to assume its normal position for the next twelve operations, and thereafter held elevated while the remaining twenty-two fastenings of the outside row are being inserted. It will be understood that by changing the position of the spring abutment 53, the starting position of the dial will be varied, and accordingly the distance which it is moved by the hand lever 70, so that the location of the inside row of fastenings may be varied as well as the number of fastenings which are inserted in said row.

The operation of the machine is as follows: After the operator has adjusted the controlling pins on the dial in the order required to produce the desired design he places the stock on the horn and elevates the rod C' to start the machine. As the main shaft revolves the arm h' is actuated to force the awl into the stock, and the frame which carries the awl bar is moved laterally to cause the awl to feed the stock, the awl being thereafter withdrawn from the stock and moved back to starting position. The

movement of the arm h' for forcing the awl into the stock operates pawl 16 to move the dial one step forward and if the first controlling pin on the dial occupies its operative position it will engage the end 24 of lever 26 and rock said lever to move the controlling lever 30 inwardly and cause its shoe 32 to engage the rolls on the pawls a^4 and hold them out of contact with the ratchet wheel a^5 of feed roll a^6 . At this point in the machine's cycle of operations the pawl carrier a^2 is actuated and the pawls a^4 carried thereby engage and rotate the ratchet wheel a^5 of feed roll a^6 for feeding the strand of wire w into the wire-receiving opening in the throat k^7 mounted on the end of shaft k^8 . The sleeve k^8 which surrounds said shaft is then oscillated to cause the cutters m and m^4 to sever the wire to form a fastening, and after the fastening has been formed the shaft k^8 is reciprocated longitudinally of the sleeve to place the fastening in the throat in alinement with the driver b^5 , which is then depressed to force the fastening out of the throat and into the stock clamped between the foot plate and the tip of the horn, the machine then having completed one cycle of operations. The dial is moved one step forward at each succeeding cycle of operations, and the feed roll a^6 is either actuated to feed the strand of wire w forward to form a fastening, or said feed roll remains inoperative, depending upon the position of the controlling pins on the dial, the pins that are in operative position actuating the lever 26 for causing the feed roll a^6 to remain inoperative, and those that are in inoperative position permitting said lever to assume its normal position to cause said feed roll to become operative for feeding said strand of wire. When the machine is stopped, the extra movement, which is imparted to lever e^2 by the tappet cam f^5 and pawl f , moves the link 42 to rock shaft 40 and thereby carries the pawl 16 and locking dog 18 out of engagement with the teeth on the dial and also moves the end of lever 26 out of position to be engaged by the controlling pins on the dial, said dial being then rotated by spring 20 back to its starting position, which is determined by the stop lever 50. When the machine is again started the spring 69 rocks shaft 40 back to normal position, and the pawl 16 and locking dog 18 are moved, respectively, by the springs 191 and 81 into engagement with the teeth of the dial, the free end 24 of lever 26 also moving into position to be engaged by the controlling pins on the dial. When it is desired to change the design in which the fastenings are to be inserted, the arrangement of the pins on the dial is changed by means of the plunger 33 and the device 35, the dial being manually rotated to bring the pins which it is desired to move into opera-

tive position into alinement with said plunger. If fastenings are to be inserted in the tread face of the heel of a right shoe in the design shown in Fig. 11 the pins on the dial are arranged as previously described, and the stop lever 50 is retained in its normal position, shown in Fig. 9, but when a left shoe is to be operated on, the hand-operated lever 70 is moved inwardly to carry the stop lever 50 in the direction of the arrow in said figure for changing the starting position of the dial.

While the preferred form of the invention is herein shown as embodied in a machine having means for feeding two strands of wire and means for governing automatically the feeding of only one strand, it will be understood that the feeding of the other strand could be governed in the same manner were it not for the fact that it is desirable to insert at each operation of the machine a fastening formed from this strand to fill the openings made in the stock by the awl, which in the machine herein shown comprises the means for feeding the stock. As previously pointed out, however, any other kind of stock-feeding mechanism may be employed without departing from the scope of the invention. Furthermore, it will be understood that the invention is not limited to a machine in which fastenings are formed from continuous material and driven into stock, but in its broadest aspect covers a machine for driving previously-formed fastenings, such, for example, as cut nails, and having means for governing automatically the operation of the mechanism that presents the nails to the driver, whereby a nail can be inserted at each successive operation of the inserting mechanism or at intermittent operations. A machine of this type could also have provision for handling a plurality of different kinds of nails for insertion either in the same row or in different rows, and in such a construction the means for governing the mechanism that presents nails of one kind to the inserting mechanism will be independent of the means for governing the mechanism that presents nails of a different kind to the inserting mechanism.

Having thus described the invention, what is claimed as new is:—

1. In a fastening inserting machine, the combination with mechanism for successively inserting fastenings, constructed and arranged to permit the presentation thereto of work of varying contours and characteristics, and means located in proximity to said inserting mechanism for engaging and intermittently feeding the work which has been presented to said mechanism, of means for automatically suspending the insertion of fastenings after a predetermined number of fastenings have been inserted and

during a predetermined number of operations of the work feeding means.

2. In a machine for inserting fastenings, means for inserting fastenings into stock, a stock support upon which the stock to be operated upon may be placed and over which it is free to move in any direction, means for engaging and intermittently feeding the stock over the stock support in a determined direction, and automatic means for causing the insertion of fastenings to be discontinued during a number of operations of the stock feeding means.

3. A fastening inserting machine comprising, in combination, means for successively inserting fastenings into stock, a stock support upon which the stock to be operated upon may be placed and over which it is free to move in any direction, intermittently operating means for engaging and feeding the stock over said stock support between the successive fastening inserting operations, and automatic means for causing the insertion of fastenings to be discontinued during a number of operations of the stock feeding means and thereafter to be resumed.

4. In a machine of the class described, mechanism for successively inserting fastenings into stock, means operating intermittently to engage and feed the stock, said inserting mechanism and said feeding means being constructed and arranged to permit the free presentation thereto of stock of varying contours and characteristics, and automatic means for causing fastenings to be inserted for a predetermined number of operations, then discontinued during a number of operations of the stock feeding means, and thereafter resumed.

5. A machine of the class described having, in combination, means for inserting fastenings constructed and arranged to permit free presentation thereto of the work to be operated upon, means operating intermittently to feed the work past the inserting means along a path determined by the contour of the work, and automatic means for causing the insertion of fastenings to be discontinued during a determined number of operations of the work feeding means.

6. A machine of the class described having, in combination, continuously operated means for inserting fastenings, means for feeding work past the inserting means in a path determined by the contour of said work, and automatic means for causing the insertion of fastenings to be discontinued during a number of operations of the work feeding means.

7. A machine of the class described having, in combination, means for inserting fastenings, a work support over which the work is freely movable, means for engaging and feeding the work over said work support

in a path determined by its contour, and automatic means for causing the insertion of fastenings to be discontinued during a number of operations of the work feeding means.

8. A machine of the class described having, in combination, continuously operated means for inserting fastenings, a work support over which the work is freely movable, means for engaging and feeding the work over said work support in a path determined by its contour, and automatic means for causing the insertion of fastenings to be discontinued during a number of operations of the work feeding means.

9. A machine of the class described having, in combination, fastening inserting mechanism, means for feeding the work between the successive operations of the inserting mechanism, means under the control of the operator for governing the starting and stopping of said inserting mechanism, and automatic means for controlling the effective operation of said mechanism while in operation whereby the insertion of fastenings may be discontinued during a number of operations of the work feeding means.

10. In a machine of the class described, continuously operated means for successively inserting fastenings, mechanism for feeding the work, said fastening inserting means and said work feeding mechanism being constructed and arranged to permit the free presentation thereto of the work to be operated upon, and automatic means for causing the insertion of fastenings to be discontinued during a number of operations of the work feeding mechanism and thereafter resumed, said automatic means being so constructed and arranged that its time of operation may be readily varied.

11. In a machine of the class described, means for inserting fastenings, mechanism for feeding the work, automatic means for causing the insertion of fastenings to be discontinued during a number of operations of the work feeding mechanism and thereafter resumed, and means for varying the time of operation of said last-named means.

12. In a machine of the class described, means for inserting fastenings, mechanism for feeding the work, automatic means for causing fastenings to be inserted for a predetermined number of times, then discontinued during a predetermined number of operations of the work-feeding mechanism and thereafter resumed, and means under control of the workman for varying the time of operation of said automatic means.

13. In a machine of the class described, means for inserting fastenings into stock, mechanism for feeding the stock, automatic means for causing fastenings to be inserted for a predetermined number of times, then

discontinued during a predetermined number of operations of the stock-feeding mechanism and thereafter resumed, and manually-controlled means for rendering the 5 automatic means inoperative for the purpose described.

14. In a machine of the class described, continuously operated means for successively inserting fastenings, intermittently 10 operated means for feeding the work in which the fastenings are inserted, said fastening inserting means and said work feeding means being constructed and arranged to permit the free presentation thereto of the work to be operated upon and automatic means for causing fastenings to be presented for insertion in any desired intermittent relation to the operations of the 15 work-feeding means.

15. In a machine for inserting fastenings into stock, continuously operated fastening inserting mechanism, stock feeding mechanism, said fastening inserting mechanism, and said stock feeding mechanism being 20 constructed and arranged to permit the free presentation thereto of the stock to be operated upon, and automatic means for causing fastenings to be presented to said inserting mechanism for insertion intermittently during the operation of the stock 25 feeding mechanism, said automatic means being so constructed and arranged that its time of operation may be readily varied to vary the spacing of successively inserted 30 fastenings.

16. In a machine for inserting fastenings into stock, fastening inserting mechanism, stock-feeding mechanism, automatic means for causing fastenings to be presented for 35 insertion intermittently during the operation of the stock-feeding mechanism, and means for varying the time of operation of said automatic means.

17. In a fastening inserting machine, the 40 combination with mechanism for successively inserting fastenings, constructed and arranged to permit the presentation thereto of work of varying contours and characteristics, and means located in proximity to 45 said inserting mechanism for engaging and intermittently feeding the work which has been presented to said mechanism, of means for automatically governing the presentation of fastenings to said inserting mechanism constructed to suspend the insertion of fastenings after a predetermined number of fastenings have been inserted and during a 50 predetermined number of operations of the feeding means.

18. In a fastening inserting machine, the 55 combination with mechanism for successively inserting fastenings, constructed and arranged to permit the presentation thereto of work of varying contours and characteristics, and means located in proximity to

said inserting mechanism for engaging and intermittently feeding the work which has been presented to said mechanism, of means for forming and presenting fastenings to the inserting mechanism, and automatic 70 means for causing the forming and presentation of fastenings to be suspended after a predetermined number of fastenings have been inserted and during a predetermined number of operations of the fastening inserting mechanism and of the feeding means.

19. In a machine of the class described, means for forming fastenings and inserting them into stock, means for feeding the stock, automatic means for causing the forming 80 and inserting of fastenings to be performed for a predetermined number of operations of the stock-feeding means, then discontinued for a predetermined number of operations, and thereafter resumed while the 85 stock-feeding means continues in operation, and means for varying the time of operation of said automatic means.

20. In a machine of the class described, means for forming fastenings and inserting 90 them into stock, means for feeding the stock, automatic means for causing the forming and inserting of fastenings to be performed for a predetermined number of operations of the stock-feeding means, then discontinued for a predetermined number of operations, and thereafter resumed while the 95 stock-feeding means continues in operation, and manually-controlled means for rendering the automatic means inoperative. 100

21. In a machine of the class described, continuously operated means for inserting a plurality of rows of fastenings, and automatic means for causing the insertion of fastenings in one row to be discontinued 105 while the machine continues in operation to insert fastenings in another row.

22. In a machine of the class described, continuously operated means for inserting a plurality of rows of fastenings, and automatic means for controlling the insertion of fastenings to cause the insertion of fastenings in the plurality of rows to be varied intermittently during the operation of the machine. 115

23. In a machine of the class described, continuously operated means for inserting a plurality of rows of fastenings constructed and arranged to permit the free presentation thereto of the work to be operated upon, 120 work feeding means, and automatic means for controlling the insertion of the fastenings to cause the insertion of fastenings in the plurality of rows to be varied intermittently as the work is fed, said automatic means being so constructed and arranged that its time of operation may be readily varied. 125

24. In a machine of the class described, means for inserting a plurality of rows of 130

fastenings, automatic means for controlling the insertion of the fastenings to cause the insertion of fastenings in the plurality of rows to be varied intermittently during the operation of the machine, and means for varying the time of operation of said automatic means.

25. In a machine of the class described, continuously operated means for inserting a plurality of rows of fastenings, and automatic means for interrupting intermittently the insertion of fastenings in one row without affecting the insertion of fastenings in any other row.

15 26. In a machine of the class described, continuously operated means for inserting a plurality of rows of fastenings, and automatic means for causing the insertion of fastenings in one row to be discontinued for a predetermined number of operations of the machine and thereafter to be resumed, without affecting the insertion of fastenings in any other row.

25 27. In a machine of the class described, continuously operated means for inserting a plurality of rows of fastenings, and automatic means for causing fastenings to be inserted in one row for a predetermined number of operations of the machine, then causing the insertion of fastenings to be discontinued for a predetermined number of operations and thereafter resumed, without affecting the insertion of fastenings in any other row.

35 28. In a machine of the class described, continuously operated means for inserting a plurality of rows of fastenings constructed and arranged to permit the free presentation thereto of the work to be operated upon, work feeding means and automatic means for causing fastenings to be inserted in one row for a predetermined number of operations of the machine, then causing the insertion of fastenings to be discontinued for a predetermined number of operations of the work feeding means and thereafter resumed without affecting the insertion of fastenings in any other row, said automatic means being so constructed and arranged that its 50 time of operation may be readily varied.

55 29. In a machine of the class described, means for inserting a plurality of rows of fastenings, and automatic means for causing fastenings to be inserted in one row for a predetermined number of operations of the machine, then causing the insertion of fastenings to be discontinued for a predetermined number of operations, and thereafter resumed, without affecting the insertion of fastenings in any other row, and means for varying the time of operation of said automatic means.

60 30. A machine of the class described having, in combination, means for inserting fastenings constructed and arranged to in-

sert a fastening at each operation of the machine to form a continuous row of fastenings, said means being also arranged to permit the free presentation thereto of the work to be operated upon, and automatic means for controlling the effective operation of said fastening inserting means whereby it is caused to insert fastenings intermittently during the operations of the machine to form also a broken row of fastenings.

75 31. In a machine of the class described, means for inserting a plurality of rows of fastenings, automatic means for causing the insertion of the fastenings forming one row to be discontinued for a predetermined number of operations of the machine and thereafter to be resumed while the insertion of the fastenings forming a different row is continued, and manually-controlled means for rendering said automatic means inoperative for the purpose described.

80 32. A machine of the class described having, in combination, means for inserting fastenings constructed and arranged to permit the free presentation thereto of the stock to be operated upon, means for feeding wire into position to be formed into fastenings, stock feeding mechanism and automatic means for discontinuing the feeding of the wire during a number of operations of the fastening inserting mechanism and of the stock feeding mechanism.

85 33. A machine of the class described having, in combination, means for inserting fastenings, means for feeding the wire into position to be formed into fastenings, stock feeding mechanism and means for automatically discontinuing the feeding of the wire for a desired predetermined number of operations of the fastening inserting means, and of the stock feeding mechanism, and thereafter resuming the feeding of the wire while the said inserting means and feeding mechanism continue in operation.

90 34. In a machine of the class described, mechanism for feeding wire into position to be formed into fastenings, means for driving the fastenings into stock, a stock support, mechanism for feeding stock over the stock support, and automatic means for causing the wire-feeding mechanism to feed the wire for any desired predetermined number of operations of the stock-feeding mechanism, then discontinue the feeding of the wire for any desired predetermined number of operations, and thereafter resume the feeding of the wire while the stock-feeding mechanism continues in operation.

95 35. In a machine of the class described, mechanism for feeding wire into position to be formed into fastenings, mechanism for inserting the fastenings thus formed, stock feeding mechanism, and means for automatically discontinuing the feeding of the wire during a number of independent op-

erations of the fastening inserting mechanism and of the stock feeding mechanism, said means being so constructed and arranged that its time of operation may be 5 readily varied.

36. In a machine of the class described, mechanism for feeding wire into position to be formed into fastenings, stock-feeding mechanism, means for automatically discontinuing the feeding of the wire during a number of operations of the stock-feeding mechanism, and means for varying the time of operation of said means.

37. In a machine of the class described, 15 means for feeding wire into position to be formed into fastenings, stock-feeding mechanism, means for automatically discontinuing the feeding of the wire during a number of operations of the stock feeding mechanism and thereafter resuming the feeding 20 of the wire, and means for varying the time of operation of said last-mentioned means.

38. In a machine of the class described, mechanism for feeding wire into position to 25 be formed into fastenings, stock-feeding means, automatic means for causing said mechanism to feed the wire for a predetermined number of operations of the stock-feeding means, then discontinue the feeding 30 of the wire while the stock-feeding means continues in operation and thereafter resume the feeding of the wire, and means for causing said automatic means to become inoperative for the purpose described.

39. In a machine of the class described, 35 means for feeding a plurality of strands of wire into position to be formed into fastenings for successive fastening inserting operations, fastening inserting mechanism for inserting the fastenings formed from the plurality of strands, and means for suspending automatically the feeding of one 40 of said strands during a number of operations of the inserting mechanism while the feeding 45 of the other strand is continued.

40. In a machine of the class described, means for feeding a plurality of strands of wire, means for severing said strands to form fastenings, continuously operated 50 mean for inserting the fastenings into stock, means for feeding the stock, and means for automatically discontinuing the feeding of one of said strands and thereafter resuming the feeding of said strand while the feeding 55 of the other strand of wire is continued and the stock-feeding means continues in operation.

41. A machine of the class described having, provision for feeding a plurality of 60 strands of wire into position to be formed into fastenings to be driven into stock and comprising means for inserting fastenings, means for causing one strand of wire to be fed at each operation of the fastening inserting means, and automatic means for

causing a different strand of wire to be fed intermittently during the operation of the fastening inserting means.

42. A machine of the class described having, in combination, means for forming fastenings from a plurality of strands of wire, means for inserting the fastenings thus formed, and automatic means for causing the forming of fastenings from one of the strands to be interrupted while the inserting 70 mechanism continues in operation to insert the fastenings formed from another strand.

43. In a machine of the class described, 75 means for inserting fastenings into stock, means for feeding the stock, controlling 80 mechanism for governing the insertion of fastenings, adjustable means for actuating said controlling mechanism automatically, and means for adjusting said automatic means to change the sequence of the operations of said controlling mechanism.

44. In a fastening inserting machine, the combination with mechanism for successively inserting fastenings, constructed and arranged to permit the presentation thereto 90 of work of varying contours and characteristics, and means located in proximity to said inserting mechanism for engaging and intermittently feeding the work which has been presented to said mechanism, of controlling mechanism for governing the operation of the inserting mechanism, and adjustable means operating in timed relation to the inserting mechanism for actuating 95 said controlling mechanism, said adjustable means being constructed to suspend the insertion of fastenings after a selected predetermined number of fastenings have been inserted and during a selected predetermined number of operations of the work 100 feeding means.

45. In a fastening inserting machine, the combination with mechanism for successively inserting fastenings, constructed and arranged to permit the presentation thereto 110 of work of varying contours and characteristics, and means located in proximity to said inserting mechanism for engaging and intermittently feeding the work which has been presented to said mechanism, of controlling mechanism for governing the presentation of fastenings to the inserting mechanism, and adjustable mechanism for actuating said controlling mechanism, said adjustable mechanism having a determined 115 starting point and being constructed to cause the presentation of fastenings to the inserting mechanism to be suspended after a predetermined number of fastenings have been inserted and during a predetermined 120 number of operations of the work feeding means.

46. In a machine of the class described, means for successively inserting fastenings into stock, means for feeding the stock be- 130

tween the operations of the inserting means, automatic means for causing the fastenings to be inserted in a predetermined design and means for controlling said automatic means constructed and arranged to cause the same design to be inserted first in right-hand and then in left-hand position with relation to the stock being operated upon.

47. In a machine of the class described, means for successively inserting fastenings into work moved into successive operative relations to said means, automatic means for causing the fastenings to be inserted in a predetermined design, and means under control of the operator for varying the action of the automatic mechanism in such manner that the fastenings will be automatically inserted in a design, the characteristic features of which are arranged in reverse order with respect to said first-mentioned design.

48. In a machine of the class described, means for successively inserting fastenings into work moved into successive operative relations to said means, automatic means for causing said fastenings to be inserted in a predetermined design in one shoe of a pair, and means for varying the action of said automatic means in such manner that the fastenings will be inserted in the other shoe of said pair in a design symmetrical with respect to said first-mentioned design.

49. In a machine of the class described, means for successively inserting fastenings into work moved into successive operative relations to said means, automatic means for causing the fastenings to be inserted in a predetermined design, and means for controlling said automatic means to cause it to provide either a right-hand design or a left-hand design.

50. In a machine of the class described, means for inserting fastenings into stock, means for feeding the stock, controlling means for governing the insertion of fastenings, a device constructed to operate said controlling means for causing fastenings to be inserted for a certain number of operations of the stock-feeding means and then to be discontinued automatically while the stock-feeding means continues in operation, means for determining the starting position of said device, and means for changing the starting position of said device to vary the time in the operation of the stock-feeding mechanism at which the fastenings are inserted.

51. In a machine of the class described, means for inserting fastenings into stock, means for feeding the stock, controlling means for governing the insertion of fastenings, adjustable mechanism constructed to operate said controlling means automatically intermittently during the operation of the machine for causing the fastenings to be

inserted in a certain design, and means for adjusting said mechanism to change the sequence of the operations of said controlling means and cause the fastenings to be inserted in a different design.

52. In a machine of the class described, means for inserting fastenings into stock, means for feeding the stock, controlling means for governing the insertion of fastenings, a dial provided with controlling pins adjustable thereon into and out of operative position and which are adapted to be arranged in the order in which it is desired to insert the fastenings in the row of fastenings inserted at operations selected from the successive operations of the machine, mechanism adapted to be actuated by said controlling pins for operating said controlling means and means for actuating said dial.

53. In a machine of the class described, means for inserting fastenings into stock, means for feeding the stock, controlling means for governing the insertion of fastenings, a dial provided with controlling pins, mechanism adapted to be actuated by said controlling pins for imparting movement to said controlling means, means for rotating said dial intermittently, and means for restoring said dial to starting position when the machine is stopped.

54. In a machine of the class described, a wire-feeding roll, a pawl carrier provided with a pawl for imparting movement to said roll, means for actuating said pawl carrier, a controlling lever adapted to engage said pawl and prevent it from moving said roll, and automatic means for actuating said controlling lever intermittently during the operation of the machine.

55. In a machine for inserting fastenings, controlling means for governing the insertion of the fastenings, mechanism for imparting movement to said controlling means, a dial provided with controlling pins for actuating said mechanism, actuating means for moving said dial forwardly, means for moving said dial rearwardly, locking means for preventing retrograde movement of said dial, and mechanism for moving said actuating means and locking means into inoperative position to permit the dial to be moved rearwardly.

56. In a machine for inserting fastenings wire feeding mechanism, a controlling lever for causing said wire feeding mechanism to become operative or inoperative, a dial provided with controlling pins adjustable thereon into and out of operative position, means operated by said pins for actuating said controlling lever, and means for imparting movement to said dial.

57. In a machine for inserting fastenings, wire-feeding mechanism, a controlling lever for causing said wire-feeding mechanism to

become operative or inoperative, a dial provided with adjustable controlling pins, a lever adapted to be actuated by the controlling pins which are in operative position, a 5 connection between said lever and said controlling lever, a pawl for imparting forward movement to said dial, a locking dog for preventing retrograde movement of said dial, and a spring for moving said dial rearwardly when said pawl and locking dog are in inoperative position.

58. In a machine for inserting fastenings, wire-feeding mechanism, a controlling lever for causing said mechanism to become operative or inoperative, a dial provided with controlling pins, means actuated by said controlling pins for operating said controlling lever, means for rotating said dial, a stop lever for determining the starting position of said dial, means for moving said stop lever to change the starting position of said dial, means for locking said stop lever in its adjusted position, and means for returning said stop lever to normal position.

59. In a machine of the class described, wire-feeding mechanism, a controlling lever for causing said mechanism to become operative or inoperative, a dial provided with controlling means, a lever adapted to be actuated by said controlling means, a connection between said lever and said controlling lever, a pawl for imparting rotative movement in one direction to said dial, a locking dog for preventing retrograde movement of said dial, means for holding said pawl and locking dog normally in engagement with the dial, a rockshaft provided with an arm that is adapted to engage said pawl and remove it from engagement with the dial, a link connected to said locking dog and adapted to be actuated by said rockshaft for removing the dog from engagement with the dial, and means for actuating said rockshaft.

60. In a machine of the class described, means for inserting fastenings into stock, controlling means for governing the insertion of fastenings, a dial provided with controlling pins, a device adapted to be actuated by said pins for imparting movement to said controlling means, means for rotating said dial, locking means for preventing retrograde movement of said dial, a rockshaft provided with means for moving said device, said rotating means, and said locking means into inoperative position, and means that is actuated automatically when the machine is stopped for operating said rockshaft.

61. In a machine of the class described, wire-feeding mechanism, controlling means for causing said feeding mechanism to become operative or inoperative, a dial, a device adapted to be actuated by said dial for

operating said controlling means, mechanism for moving said dial forwardly, locking 65 means for preventing retrograde movement of said dial, manually-operated means for causing said device, said dial-moving mechanism, and said locking means to be moved into inoperative position, and means for returning said dial to starting position.

62. In a machine of the class described, a plunger mounted in a stationary part of the frame of the machine, a dial having adjustable controlling pins and adapted to be rotated to bring any one of the controlling pins into position to be engaged by said plunger, and manually-operated means for locking the dial in position.

63. In a machine of the class described, a dial rotatably mounted on a stationary stud and provided with adjustable controlling pins, a plunger mounted in a stationary bearing and adapted to be actuated for moving the controlling pins on the dial into operative position, and a device rotatably mounted on said stud and adapted to be actuated for moving said controlling pins into inoperative position.

64. In a machine of the class described, a dial rotatably mounted on a stationary stud, means for determining the starting position of said dial, means for rotating said dial forwardly in one direction, means for preventing the dial from making more than one 95 complete revolution, and means for rotating the dial in the opposite direction back to starting position.

65. In a machine of the class described, a dial, means for actuating said dial, a stop 100 lever for determining the starting position of said dial, and an adjustable abutment for determining the normal position of said stop lever.

66. In a machine of the class described, 105 means for feeding a plurality of strands of wire, means for severing said wire to form fastenings, means for driving the fastenings into stock, an awl, mechanism for actuating said awl to feed the stock, a controlling lever 110 for governing the feeding of one strand of wire, a dial provided with controlling pins adapted to be arranged in the order in which it is desired to insert the fastenings into the stock, mechanism actuated by said pins for 115 imparting movement to said controlling lever, and means operated by the awl-actuating mechanism for imparting movement to said dial.

In testimony whereof I have signed my 120 name to this specification in the presence of two subscribing witnesses.

FREDERICK H. PERRY.
